[57] CLAIM

The ornamental design for a green bean and pea sheller, as shown and described.

DESCRIPTION

FIG. 1 is a perspective view of a green bean and pea sheller showing my new design, the side not shown being substantially a mirror image of the side shown, except for the omission of the power input shaft and the circular opening therefor;

FIG. 2 is a front elevational view thereof; and,

FIG. 3 is a rear elevational view thereof.
